CLAIM

The ornamental design for a fog applicator for pesticide and herbicide chemical dispersion, as shown and described.

DESCRIPTION

FIG. 1 is a perspective view of a fog applicator for pesticide and herbicide chemical dispersion showing our new invention;

FIG. 2 is a top plan view thereof;

FIG. 3 is a front elevational view thereof;

FIG. 4 is a left side elevation view thereof, the right side being a mirror image;

FIG. 5 is a rear elevational view thereof;

FIG. 6 is a bottom plan view thereof; and

FIG. 7 is an enlarged view looking directly into a nozzle portion thereof.

FIG. 1.

FIG. 2.

FIG. 4.

FIG. 3.

FIG. 5.

FIG. 7.

FIG. 6.
